UNITED STATES PATENT OFFICE.

MERT T. BUCKLEY, OF WICHITA, KANSAS.

VENTILATOR.

Application filed September 12, 1922. Serial No. 587,649.

To all whom it may concern:

Be it known that MERT T. BUCKLEY, a citizen of the United States of America, residing at Wichita, in the county of Sedgwick and State of Kansas, has invented 5 certain new and useful Improvements in Ventilators, of which the following is a specification.

My invention relates to ventilators and 10 more particularly to siphon ventilators.

The principal object of the invention is to obtain a maximum outside and inside air capacity and maximum siphoning action for a ventilator of given size.

15 Other and further objects and advantages of the invention will be in part explained and in part obvious as the specification is proceeded with.

In the accompanying drawings:

20 Figure 1 is a side elevation of my invention;

Figure 2 is a similar view partly broken away; and

25 Figure 3 is a top plan view partly broken away.

Referring more particularly to the drawings, 5 denotes the tubular body portion or base pipe of the ventilator which communicates at its lower end with the usual vent 30 pipe (not shown). This tubular body portion is connected at the upper end or is integrally formed at said upper end with an outwardly flared tube 6. Extending around the tube 6 scalloped at its top edge, are circumferential rows of vertically alined air 35 inlets 7, formed by slotting the tube 6, at intervals in a horizontal plane and pressing inwardly that portion of the tube directly beneath the slots to form ducts. The extent 40 of the flare of the tube 6, as well as the size and number of inlets 7, will be determined or regulated according to the size of the base 5.

A downwardly and outwardly flared flange 8, is connected at its upper edge with 45 the base tube 5, at the point of juncture between the latter and the upwardly and outwardly flared slotted tube 6. This flange serves to direct the outside currents of air upwardly to the interior of the base tube 50 for an obvious purpose.

Vertically disposed spaced fins 9, secured to the tube 6, support a downwardly and outwardly flared skirt member 10, which encloses the entire tube 6, and a portion of the 55 base tube 5, and serves as a jacket for siphoning the outside air upwardly between

the skirt and the tubes and thence inwardly through the air ducts 7. The fins 9, also separate the outside air delivering the same through the several different pockets 11, 60 thus formed.

The cone shaped top 12, of the ventilator is secured in place and supported by means of outer fins 14, secured to the outside of the skirt 10, at the upper end thereof and to 65 ring 13 which braces the top of skirt 10. These outer fins 14, also serve to break up the upwardly flowing outside air currents passing between the skirt and the outer band 15, connected to the fins 14 and encircling 70 the top 12, in spaced relation thereto. The outer upper fins 14, are preferably arranged in staggered relation to the inner lower fins 9. By this staggered arrangement, air currents not directly in the space between two 75 lower fins are directly in the space between upper fins, thereby insuring a better flow.

From the foregoing it is thought the operation of the invention will be clear, but the same may be briefly described as follows: 80 The outside air currents passing respectively between the flange 8, and the skirt 10 and through the slots 7, between the skirt 10, and the tube 6, and between the band 15, and the skirt create a siphoning action 85 on the inside of the tubes 5 and 6 thereby accelerating the escape of the inside air. As the two currents of air, one from the inside of the building to be ventilated and the other from the atmosphere require more 90 space than is provided by the base tube 5, the tube 6, which is in effect an extension of the base tube 5, is outwardly flared to provide the increased volume necessary to accommodate both the inside and the outside air, thus preventing the checking of the flow of the inside air. By arranging the air ducts in vertical alignment, they materially air each other, the combined number 95 in a tier, siphoning the air upward until 100 the other air currents grasp it and take it out.

Having thus described my invention, what I claim as my invention is:

1. A ventilator comprising a base pipe 105 having an upwardly and outwardly flaring slotted extension, an outwardly and downwardly flared flange secured to said base at its point of joinder with the said extension, spaced fins secured to said base and said extension, an outwardly and downwardly flared skirt secured to said fins and enclosing 110

said extension, fins attached to the outside of said skirt at its upper end; and a ventilator top and top band supported by said last mentioned fins, the two sets of fins being in staggered relation one to the other.

2. A ventilator comprising a base pipe having an upwardly and outwardly flaring extension, said extension provided with circumferential rows of vertically aligned slots, an outwardly and downwardly flared flange secured to said base at its point of joinder with the said extension, spaced fins secured to said base and said extension, an out-

wardly and downwardly flared skirt secured to said fins, and enclosing said extension, fins attached to the outside of said skirt at its upper end, and a ventilator top and top band supported by said last mentioned fins, the two sets of fins being in staggered relation one to the other.

In testimony whereof I affix my signature in presence of two witnesses.

MERT T. BUCKLEY.
